UNITED STATES PATENT OFFICE

167,458

RACK FOR COMBS OR SIMILAR ARTICLES

Peter J. Gulotta, Rockford, Ill.

Application December 21, 1951, Serial No. 17,798

Term of patent 14 years

(Cl. D33—3)

To all whom it may concern:

Be it known that I, Peter J. Gulotta, a citizen of the United States, residing at Rockford, in the county of Winnebago and State of Illinois, have invented a new, original, and ornamental Design for a Rack for Combs or Similar Articles, of which the following is a specification, reference being had to the accompanying drawing, forming part thereof.

In the drawing:

Fig. 1 is a perspective view of a rack for combs or similar articles embodying my new design;

Fig. 2 is a front elevational view on a larger scale;

Fig. 3 is a side elevational view; and

Fig. 4 is a top plan view.

I claim:

The ornamental design for a rack for combs or similar articles, as shown.

PETER J. GULOTTA.
